ELECTRONIC TRANSLATING DEVICE

Herbert Ziebolz, Chicago, Ill., assignor, by mesne assignments, to Electronbeam, Ltd., Chicago, Ill., a partnership of Illinois

Application July 24, 1942, Serial No. 452,222

12 Claims. (Cl. 315—32)

This invention relates to electronic translating devices for relaying, amplifying, converting, transforming or otherwise translating electric signals, or signals of any nature which may be converted by known means into electric signals. The invention is useful in translating signals or variations representing physical, chemical or other conditions. The invention is also useful for converting mechanical movements or displacements as of an object into corresponding electric variations which may be employed to control other devices or to operating indicating or recording devices for indicating or recording the mechanical movements or displacements.

One object of the invention is to devise a translating device or relay in which variations in the output energy are directly proportional to the variations in the input signal.

A further object is to devise a highly sensitive translating device embodied within an evacuated container forming the envelope of an electronic tube.

The invention disclosed herein is useful generally for the same purposes as the electronic relay disclosed in my earlier filed application Ser. No. 417,871, filed November 4, 1941. My earlier translating device involves a cathode ray tube in which the cathode ray beam is deflected by an input deflecting means energized or operated from a suitable input signal or variation to produce corresponding variations in the output circuit of the translating device. In order to obtain proportional variations in the output circuit, energy variations in the output circuit are employed to set up a second deflecting force in opposition to the input deflecting force to establish equilibrium of the two deflecting forces.

The present invention differs broadly from the earlier form of my translating device in that instead of employing a cathode ray type of tube, an electronic tube having one or more movable electrodes is employed to vary the electron flow in one or more electron paths. The input signal or variation is utilized to produce a movement of at least one movable electrode and thereby produce a change in current flowing between at least two electrodes of the tube, and this variation in current is employed to establish an opposing force acting upon the movable electrode tending to establish equilibrium between the two opposing forces.

A special feature of the invention is that the arrangements for mounting the movable electrodes are arranged wholly within the envelope of the tube and permit free movement of the

electrodes with a minimum amount of friction or restraining force.

A number of embodiments of my invention are illustrated in the accompanying drawing, in which

Fig. 1 is a diagrammatic representation of one construction of translating device in which two movable anodes of the electronic tube are mounted on a pivot lever or beam wholly enclosed in the tube envelope; and magnetic inductive means are employed for applying a deflecting force to the lever from the input source and also an opposing force from the output circuit;

Fig. 2 shows an arrangement employing two stationary cathodes and one movable anode mounted on the movable lever and in which electrostatic means is employed to apply both the input force and the counterbalancing force to the lever;

Fig. 3 is a diagrammatic representation of a third modification in which the electronic tube embodies a stationary cathode and two stationary anodes with two movable grids interposed in the two electronic paths, the two grids being mounted upon the pivoted lever of a modified Kelvin balance; and

Fig. 4 is a fragmentary view showing a modification of the translating device in which the input force acting on the movable electrode support is applied by mechanical movement of a control element located externally of the tube.

Referring to Fig. 1, the electronic tube is formed of an insulating envelope 10 enclosing an electron emitting cathode 11 which is energized by a suitable source represented by the battery 12. Two anode elements 13a and 13b are positioned on opposite sides of the cathode, and these anodes are maintained at a positive potential with respect to the cathode by means of a suitable source represented by the battery 14, the negative terminal of the source being connected to the cathode through the adjustable connection on the potentiometer 14a connected across the source 12. Suitable coupling resistances 13c and 13d are inserted in the circuits of anodes 13a and 13b respectively. As shown in the drawing, anodes 13a and 13b are mounted for relative movement with respect to the cathode 11 so that as one anode moves closer to the cathode, the other moves away from the cathode. One suitable mounting arrangement involves the lever 15 which is pivoted near its center to a suitable support 10a, the two anodes 13a and 13b being supported on the lever in insulated relation and in proper position with respect to the cathode

11. The electric signals or variations to be translated are applied to the terminals 16 and serve to energize the magnetic coil 16a surrounding an extension 10b formed in one side of the tube 10 adjacent one end of the lever 15. The coil 16a acts inductively on a magnetic core member 16b carried by the lever 15 and positioned to extend into the extension 10b. A second inductive coil 17 is positioned on a second extension 10c formed in the wall of the tube 10 opposite extension 10b, and this coil acts upon a second inductive core 17a carried by the lever 15 and extending into the extension 10c.

Potential variations developed between anodes 13a and 13b are applied to the output circuit terminals 18 either directly or through a suitable amplifier 19. Coil 17 is energized from the output circuit and exerts a force on lever 15 in opposition to the force exerted on the lever by coil 16a. A suitable meter 20 indicates the value of current supplied to the coil 17.

The operation of Fig. 1 is as follows: It will be assumed that with no signal applied to the coil 16a, lever 15 is in its neutral position and equal currents flow in the two anode circuits. Under this condition, no potential difference is developed between the two anodes, and no voltage is applied to the output circuit or to the coil 17. As soon as the coil 16a is energized by a signal, a force is applied to the lever 15 tending to rotate it in a clockwise direction, thus tending to increase the current in the circuit of anode 13b and decreasing the current in the circuit of anode 13a. The resulting potential difference between the two anodes impresses a corresponding potential difference on the output circuit and causes a current to flow in coil 17 which opposes the force exerted on the lever 15 by the input coil 16a. The lever 15 will assume a position where the two forces are in equilibrium, that is, where the force of coil 17 tending to rotate the lever anti-clockwise is equal to the force of the coil 16a tending to rotate the lever clockwise. The amount of deflection of the lever 15 from its normal position is dependent upon the value of the input signal, and the amount of current supplied to coil 17 necessary to counterbalance the input force will necessarily vary in accordance with variations in the input signal. Accordingly, the indications on the meter 20 will vary in direct proportion to the strength of the input signal and meter 20 may be calibrated in units appropriate to the input signal. The circuit as shown is useful for measuring or indicating the input signals. The circuit is also useful for controlling purposes by connecting the control apparatus to the output terminals 18, as will be understood by those skilled in the art.

The inductive cores 16b and 17a may be formed of soft iron or of permanent magnets. Also, the deflecting force may be applied to the lever by the interaction of two or more coils, one of which is carried by the lever, as is shown in Fig. 3. It is not essential that two movable anodes be employed; only one may be used since the output circuit could be energized in accordance with potential variations developed across either coupling resistance 13c or 13d.

In Fig. 2 elements which have the same function as corresponding elements in Fig. 1 are represented by corresponding reference numerals. In this arrangement, only one anode 13 is carried by the lever 15 and is mounted for movement between two spaced cathodes 11a and 11b energized respectively by sources 12a and 12b. The anode

13 is maintained at a positive potential with respect to the cathodes by the source 14, two coupling resistances 13c and 13d being interposed in the two electron current circuits. The output circuit 18 is energized in accordance with potential variations developed between the two cathodes.

Fig. 2 also shows a variation in the manner of applying the deflecting force to the lever 15, but it will be understood that the arrangement shown in Fig. 1 may be used if desired. In Fig. 2, signals from the input circuit 16 are applied to conducting plates 21a and 21b forming a condenser arrangement, one plate being stationary, while the other is carried by the lever 15. The electrostatic action between the two plates will exert a deflecting force on the lever 15 which will vary in accordance with the value of the input signal. The counter-balancing force may also be applied to the lever 15 from the output circuit by applying the output potential between plates 22a and 22b, one of which is stationary and the other being carried by the lever 15. In this case, a voltmeter 20a is connected to indicate the value of the output voltage which also serves to indicate the value of the input signal. It is believed that the operation of Fig. 2 will be clear in view of the foregoing description of the operation of Fig. 1.

In Fig. 3 the electron tube construction involves a single stationary cathode 11 and two stationary anodes 13a' and 13b' with two movable interposed grids 23a and 23b. The grid elements are carried by the right end of pivoted lever 15 and are suitably insulated from this lever. The cathode heating circuit and the anode supply circuits for Fig. 3 are the same as in Fig. 1. The two grid elements are connected together and may be maintained at a desired potential, preferably negative, with respect to the cathode 11 by means of a biasing battery 24. The output circuit connections for Fig. 3 are the same as in Fig. 1.

The arrangement for applying the input deflecting force and the counterbalancing force to the lever 15 involves a modified Kelvin balance arrangement in which the input circuit 16 supplies current to two stationary coils 16a and 16a' arranged on opposite sides of a movable coil 16c carried by the lever 15. The interaction of these three coils exerts a force on lever 15 tending to unbalance the level in a well known manner. The three coils are connected in series, but it will be understood that the stationary coils may be separately excited and the movable coil may be connected to the input circuit, or vice versa. The counterbalancing force is applied to the lever 15 by means of two stationary coils 17 and 17b acting on a movable coil 17c carried by lever 15, the three coils being connected in series and supplied with current from the output circuit 18 through a current meter 20. The same variations in connections of these three coils is possible as in the case of the input coils. Also, any of the stationary coils may be located outside of the tube envelope if desired.

The operation of Fig. 3 is believed to be clear in view of the foregoing description of the operation of Fig. 1. In this arrangement, however, the two electron paths are not varied in length, but the amount of electron flow in the two paths is varied in opposite directions by movement of the two grids 23a and 23b with respect to the cathode 11.

Fig. 4 shows a further variation of the translating device in which the input signal or variation is in the form of movement of an element 75 or member. In this arrangement, the movement

to be indicated, measured, repeated or translated, is applied to a movable rod 16' which carries a magnetic yoke 16'', preferably in the form of a permanent horseshoe type of magnet. The magnet 16'' has its opposing arms positioned on opposite sides of extension 16b. The two arms have inwardly projecting pole pieces which act inductively on magnetic bar 16b' carried by the end of lever 15. The arrangement is otherwise like the arrangement shown in Fig. 1, although many variations are possible.

It will be understood that the movement to be measured or indicated is applied to the rod 16' which imparts corresponding movement to the magnet 16'' which in turn imparts corresponding movement to the magnetic bar 16b' and thus to the lever 15. The arrangement at the other end of the lever 15 may be in accordance with any of the arrangements shown above, and the operation will be clear to those skilled in the art.

In the appended claims the term "inductive means" is used in a broad sense to apply to the capacity inductive means shown in Fig. 2 as well as to the magnetic inductive means shown in Figs. 1, 3 and 4. It is obvious that various combinations of capacity and magnetic inductive means may be used. For example, the input inductive means may be of the capacity type while the counterbalancing inductive means may be of the magnetic type, or vice versa.

What is claimed is:

1. An electronic translating device, comprising an electronic tube having an enclosing envelope, two electrodes mounted within said envelope, one of which emits electrons, a circuit including a source of current for establishing current flow between said electrodes, a movable member wholly within said envelope mounting one of said electrodes for movement towards and away from the other electrode to vary the electrons flowing in the electron path between said two electrodes and thereby varying the current in said circuit, input means coupled to said movable member for effecting movement of said movable member, and means in said circuit and controlled by the current flowing therein for applying a variable force to said movable member in opposition to the force applied by said input means.

2. A translating device according to claim 1, wherein said movable member is a balanced lever pivotally supported in said tube envelope.

3. A translating device according to claim 1, wherein the input means for effecting movement of the movable member comprises an input inductive means coupled with the movable member.

4. A translating device according to claim 1, wherein the input means for effecting movement of said movable member comprises an inductance element inductively coupled through the envelope with the movable member and the means responsive to variations in current flowing in said electron path likewise comprises an inductance element acting inductively on said movable member in opposition to the input inductance element.

5. An electronic translating device, comprising an electronic tube having an elongated enclosing envelope, a plurality of electrodes mounted in one end of said envelope, one of said electrodes being an electron emitting element, a circuit including a source of current for establishing cur-

rent flow between said electrodes, a movable lever mounted entirely within the envelope and carrying one of said electrodes for movement relative to another of said electrodes to vary the electrons flowing in an electron path between two of said electrodes included in said circuit, an inductive element carried by said lever, input means for acting inductively on said inductive element to apply a force to and cause movement of said lever, and means in the circuit of said source responsive to variations in the flow of current in said circuit for exerting an opposing force on said lever to establish equilibrium between said forces.

15 6. A translating device according to claim 5, wherein the movable lever is pivotally mounted at a point intermediate the ends thereof within the envelope, said movable electrode and said inductive element being mounted upon said lever on opposite sides of the pivotal point thereof.

20 7. An electronic translating device, comprising an electronic tube having an elongated enclosing envelope, a plurality of electrodes mounted in one end of said envelope, one of said electrodes being an electron emitting element, a movable lever mounted entirely within the envelope and carrying two of said electrodes for movement relative to said electron emitting element, circuit connections between said electron emitting element and said two electrodes and including a source of current for establishing current flow between said electron emitting element and said two electrodes carried by said lever, an inductive element carried by said lever, input means 25 coupled inductively to said inductive element for applying a force to and cause movement of said lever, counterbalancing means carried by said lever for exerting an opposing force on said lever, and circuit connections from said electrodes carried by said lever to said counterbalancing means for energizing said counterbalancing means in accordance with the difference of potential between said two electrodes.

30 8. A translating device according to claim 5, 45 wherein the lever carries a single anode movable between two spaced electron emitting elements.

9. A translating device according to claim 5, wherein said electron emitting element is stationary, and said plurality of electrodes includes a pair of grid electrodes carried by said lever and mounted for movement on opposite sides of said electron emitting element, and including a pair of stationary anodes mounted on opposite sides of said electron emitting element and co-55 operating therewith.

10. A translating device according to claim 5, wherein said inductive element on the lever extends into an extension on the envelope and including magnetic field producing means embracing said extension for influencing said inductive element.

11. A translating device according to claim 5, wherein the inductive element carried by the lever comprises a conducting plate forming one 60 element of an electric condenser and is influenced by another plate constituting the other element of the condenser.

12. A translating device according to claim 5, 70 wherein the inductive element carried by the lever is in the form of one coil of a Kelvin balance.

HERBERT ZIEBOLZ.
